US00D855587S

(12) **United States Design Patent** (10) **Patent No.:** **US D855,587 S**
(45) **Date of Patent:** **** Aug. 6, 2019**

(54) **PLAYBACK DEVICE**

- (71) Applicant: **Sonos, Inc.**, Santa Barbara, CA (US)
- (72) Inventors: **Stefan Reichert**, Santa Barbara, CA (US); **Mieko Kusano**, Santa Barbara, CA (US); **Roland Bird**, Eindhoven (NL); **Roger Swales**, Eindhoven (NL); **Niels van Hoof**, Eindhoven (NL); **Lukasz Natkaniec**, Munich (DE); **Dana Krieger**, Santa Barbara, CA (US); **Tadeo T. Toulis**, Santa Barbara, CA (US); **Mike Chamness**, Santa Barbara, CA (US); **Hilmar Lehnert**, Santa Barbara, CA (US); **Wilfred Wei**, Shanghai (CN); **Wei Hean Liew**, Santa Barbara, CA (US)
- (73) Assignee: **Sonos, Inc.**, Santa Barbara, CA (US)
- (**) Term: **15 Years**
- (21) Appl. No.: **29/627,445**
- (22) Filed: **Nov. 27, 2017**

Related U.S. Application Data

- (63) Continuation of application No. 29/577,674, filed on Sep. 14, 2016, now Pat. No. Des. 806,678, which is (Continued)
- (51) **LOC (12) Cl.** **14-01**

CLAIM

The ornamental design for a playback device, as shown and described.

DESCRIPTION

FIG. 1 is a front view of a playback device, according to our new design;
FIG. 2 is a rear view thereof;
FIG. 3 is another rear view thereof;
FIG. 4 is a top view thereof;
FIG. 5 is a bottom view thereof;
FIG. 6 is a left view thereof;
FIG. 7 is a right view thereof;
FIG. 8 is a perspective view thereof;
FIG. 9 is another perspective view thereof;
FIG. 10 is another perspective view thereof;
FIG. 11 is another perspective view thereof, showing an enlarged and isolated portion of the article; and,
FIG. 12 is an interior view of a playback device shown according to our new design.
The broken lines illustrate portions of the drawings that form no part of the claimed design.

1 Claim, 12 Drawing Sheets

Related U.S. Application Data

a continuation of application No. 29/525,027, filed on Apr. 25, 2015, now Pat. No. Des. 768,602.
